LOUIS RANSOM, OF LANSINGBURG, NEW YORK, ASSIGNOR, BY MESNE ASSIGNMENT,
TO LOUIS RANSOM AND EUGENE HYATT, OF SAME PLACE.

Letters Patent No. 32,988, dated October 13, 1868.

IMPROVEMENT IN CLASPS FOR TRUNKS, &c

The Schedule referred to in these Letters Patent and making part of the same.

To all whom it may concern:

Be it known that I, LOUIS RANSOM, of Lansingburg, in the county of Rensselaer, and State of New York, have invented a new and useful Improvement in Clasps for Trunks and other similar articles; and I do hereby declare that the following is a full, clear, and exact description thereof, reference being had to the accompanying drawings, and the letters of reference marked thereon.

The clasp, which forms the subject-matter of this invention, is designed to be used on cylindrical trunks, made in pursuance of Letters Patent granted to me, bearing date the 20th day of August, 1867, but it may be applied to trunks, boxes, &c., of other forms.

In the accompanying drawings—

Figure 1 is a side elevation of the clasp;

Figure 2 is a central longitudinal section of the same; and

Figure 3 is a top view.

The clasp consists of two separate parts, A and B. The part A is attached to the body of the trunk, and the part B to the lid. Each of said parts, A and B, has a central longitudinal slot, e and e', in which a tongue, c, fits, said slots so coinciding as to form a continuous slot to receive the tongue c when the lid is closed. Said slot e', in the part A, is enlarged at its inner end to receive the head c' of the tongue, said enlargement corresponding in form with the said head

c', as shown in fig. 3. Said tongue c is pivoted at f to the part B, and a spring, d, presses against the lower end of said tongue to keep it in position when shut down, or, when open, acting upon the same principle as the spring of a common pocket-knife upon the blade thereof. Said tongue c is provided with a thumb-catch, i, to raise it, for the purpose of opening the trunk. When the tongue is shut down, its outer surface is flush with the outer surface of A and B, and its head c fits into the recess r in A, so that the lid cannot open unless the tongue be raised. It is manifest that a catch or hook of different form from the head c' may be made on the end of the tongue c, to perform the same function.

This clasp is intended as a substitute for the straps and buckles in common use on trunks. It is not only much more convenient, on account of the less time required in adjusting it, but it more effectually prevents the vibration or "chucking" of the lid.

What I claim as my invention, and desire to secure by Letters Patent, is—

A trunk-clasp, consisting of the two parts A and B, the clasp-tongue c, and spring d, constructed, combined, and operating substantially as described.

LOUIS RANSOM.
